UNITED STATES PATENT OFFICE.

WALLACE S. ANDREWS, OF SYRACUSE, NEW YORK.

WATER-HEATER FOR GAS-STOVES.

1,217,678.

Specification of Letters Patent. Patented Feb. 27, 1917.

Application filed April 24, 1915. Serial No. 23,640.

To all whom it may concern:

Be it known that I, WALLACE S. ANDREWS, a citizen of the United States of America, and a resident of Syracuse, in the county of 5 Onondaga, in the State of New York, have invented new and useful Improvements in Water-Heaters for Gas-Stoves, of which the following, taken in connection with the accompanying drawings, is a full, clear, and 10 exact description.

This invention relates to certain improvements in water heaters for gas stoves having one or more burners below the top thereof.

These gas stoves or ranges are usually 15 provided with a depressed marginal flange extending entirely around the burner or system of burners for receiving and supporting the marginal edges of one or more grills or grids which are loosely seated upon the 20 flange and may be removed at will to permit access to the burners and underlying portions of the stove for cleaning and other purposes, and also serves to support cooking utensils over the flame of the burners.

25 It is well known that when these utensils are placed upon the grid over the burner, the flame is deflected laterally or radially in all directions and that a considerable amount of heat generated by the burner is lost, and 30 the main object of my present invention is not only to utilize this waste heat in heating the water of a storage tank, but also to permit the water-heating shell or plate to be used in place of the usual grill or grid, that 35 is, I have sought to provide a substantially flat yet hollow water-containing plate of substantially the same outline and area as the grid or grill so that the latter may be removed and replaced by the plate with its 40 marginal edges resting upon the depressed flange around the system of burners and its intermediate portion formed with circular openings corresponding in number to and registering with said burners.

45 Another object is to provide means for connecting this water-containing plate to a suitable reservoir or tank where hot or warm water may be held in reserve for use in different parts of the house where necessary or 50 desirable.

Other objects and uses will be brought out in the following description.

In the drawings—

55 Figure 1 is a perspective view of a gas range with my improved water heater thereon.

Fig. 2 is an enlarged horizontal sectional view through the water plate.

Fig. 3 is a transverse vertical sectional view of the same plate and adjacent portion 60 of the top of the range or gas stove.

The gas stove or range as —1— is provided with the usual top —2— having an opening —3— of sufficient size to surround a system of burners —4—, said top being provided with a depressed flange —5— surrounding the opening —3— for receiving and supporting the usual grill or grid which is now removed and replaced by my invention consisting of a substantially flat hollow 65 water-containing shell —6—. The usual heat escape pipe 1^a projects upwardly from the stove top at the rear side thereof.

This shell is substantially rectangular and of just sufficient length and breadth to permit its marginal edges to rest loosely upon the marginal flange —5—, thereby covering the opening —3—, said shell having its lower and upper walls substantially flat and parallel forming an interior relatively shallow 70 water chamber —7—. The rear side of the shell is curved inwardly at the central portion as at 6^a to provide a clearance space for the heat escape pipe. The main body of the shell is provided with vertical openings —8— 75 corresponding in number to and registering with the burners —4— to permit the heat to pass from the burners through the opening for heating any cooking utensils which may be placed upon the upper surface of the shell 80 —6— over said openings.

A partition —9— extends from one side, preferably the rear side of the shell —6— partially across the interior of the plate substantially midway between its ends and 95 apart from the walls of the openings —8—, and also between the water supply pipe —10— and a return pipe —11— leading to and from the interior of the shell, the partition —9— serving to cause the water to 100 circulate through all parts of the interior of the shell and entirely around the walls of each of the openings —8—.

These supply and return pipes —10— and —11— may be connected to a suitable water 105 circulating system, including therein a hot water reservoir, not shown, but to which the heated water may be directed from the water heater —6—.

The upper ends of each of the openings 110 —8— may be slightly enlarged to form an annular griddle seat —12— for receiving a

griddle as —13— with its upper face coincident with that of the top of the shell and when necessary may be placed in operative position to restrain the upflow of the heated air from the burners —4— and cause the heated products to impinge against the walls of the openings to heat the water in the interior of the shell —6—, although the presence of a kettle or other utensil over the opening will perform the same function and the intention is to utilize the heat which would otherwise be wasted during cooking operations in heating the water in the shell —6— and storing such heated water in a suitable reservoir, not shown, for subsequent use.

What I claim is:

A water heater for gas stoves having the usual flat top and heat escape pipe projecting upwardly from the top, said heater comprising a one-piece hollow casting composed of flat bottom and top walls having coaxial vertical openings for registration with the

gas burners, said walls being held in parallel spaced relation by marginal walls uniting their outer edges and by circular walls uniting the edges around the openings and also by a partition uniting the central portions thereof, the rear marginal wall being curved inwardly to provide a clearance space 25 for the heat escape pipe, and with the partition extending forwardly from the curved portion, said partition extending forwardly from the center of the rear marginal wall between said openings and to a point a short 30 distance from the front marginal wall, and out-flow and return pipes secured to the rear marginal wall at opposite sides of the partition.

In witness whereof I have hereunto set 40 my hand this 17th day of April, 1915.

WALLACE S. ANDREWS.
